Primary Examiner—Dominic Simone**Attorney, Agent, or Firm**—Young & Thompson**[57] CLAIM**

The ornamental design for a jewelry box, as shown and described.

DESCRIPTION

FIG. 1 is a top, front and left side perspective view of a first embodiment of a jewelry box, showing my new design; FIG. 2 is a top plan view thereof; FIG. 3 is a front elevational view thereof; FIG. 4 is a right side elevational view thereof, the left side elevational view being the mirror image thereof; and, FIG. 5 is a bottom plan view thereof. The side opposite that shown in FIG. 3 is plain and unornamented.
